UNITED STATES PATENT OFFICE.

PATRICK RYAN, OF ASTORIA, NEW YORK.

APPARATUS FOR TAKING AND PRESERVING FINGERPRINT IMPRESSIONS.

Application filed March 29, 1922. Serial No. 547,667.

To all whom it may concern:

Be it known that I, PATRICK RYAN, a citizen of the United States, and resident of Astoria, New York city, borough of Queens, in the county of Queens and State of New York, have invented certain new and useful Improvements in Apparatus for Taking and Preserving Fingerprint Impressions, of which the following is a specification, reference being had therein to the accompanying drawing.

My present improvements relate to devices or apparatus for assisting in the taking and preservation of finger print impressions, and consist primarily in a simplified and economical machine, capable of doing effective and lasting service without liability of breakage or a disordering of the parts.

It should be remarked that in the present rapid development of the practice of finger print taking and their preservation for record purposes in the way of identification and otherwise, the value of mechanical devices for assisting in the work is becoming recognized more and more extensively every day, and it is seen to be very necessary that such devices should be strong, durable, cheap, simple, and easily understood and operated by all classes and grades of employees and other persons, unskilled as well as skilled, in governmental departments, courts, banks, stores, and all kinds of offices and institutions, as well as wherever finger print records are found useful and desirable.

My object therefore is to provide an apparatus or machine that will be suitable for all these needs among many that might be mentioned.

In the mechanical features of the invention I provide improved means whereby the recording surface for the prints, such as a filing card or blank, may be an easy manipulation of a handle and without any soiling or breakage of the recording surface by the operator's fingers be guided and fed surely and gradually and to any degree required over the edge of the recording table and retained in different positions on the finger impressing bed to enable all the parts of such recording surface to be quickly available for receiving the impressions of several subjects thereon in any desired succession or relation.

With these and other objects in view, my present invention may be said to consist essentially in the construction, arrangement,

and combination of parts, and in numerous details and peculiarities of the same, substantially as will be hereinafter more fully described and then expressly pointed out in the ensuing clauses of claims.

In the accompanying drawings illustrating my invention:

Figure 1 is a side elevation of my improved finger-print apparatus, with the parts in the unfolded position they occupy when extended for actual use.

Figure 2 is a similar side elevation of the apparatus when folded up to occupy as little space as possible for storing or portability.

Figure 3 is a front elevation of the apparatus shown in Figure 1, with certain parts in section.

Figure 4 is a top plan view of the base that carries the ink and ink-distributing appliances.

Figure 5 is a horizontal sectional detail on the line 5, 5, of Figure 3.

Figure 6 is a plan view of the main table or impression bed and contiguous parts, with the main frame in section.

Figure 7 is a sectional detail on the line 7, 7, of Figure 1.

Figure 8 is a vertical cross-sectional elevation on the line 8, 8, of Figure 3.

Figure 9 is a vertical cross-sectional elevation on the line 9, 9, of Figure 6.

Similar characters of reference designate corresponding parts throughout all the different figures of the drawing.

The main frame is composed of as few parts as possible, so as to insure lightness and simplicity. This frame comprises chiefly a base 1, on which are mounted two parallel side uprights 2, 2, to the upper ends of which are pivoted by means of horizontal pins 18, see Figure 6, the extension arms 3, 3, which are secured together by the horizontal tie-rod 5 having the end nuts 31, and are adapted to occupy a vertical position substantially in line with and above the uprights 2, 2, when the machine is open in position for use, as shown in Figure 1, or to fold down alongside of the uprights 2, 2, when the machine is idle, as indicated in Figure 2. These extension arms 3, 3, have terminal angular castings 4, 4, shaped with inclined holders for the finger-inking or ink-applying platen 6, to which the fingers are pressed to ink them in readiness for printing. And the uprights 2 are conveniently provided with right-angled feet

49 that are secured to base 1 by means of screws 50 or other means.

The finger-inking platen 6, which is mounted at the top of the apparatus, as clearly shown in Figures 2 and 3, is preferably disposed in an inclined position when normally placed for use, in order that it can be more readily approached. It is usually a narrow oblong slab of suitable material, 10 as for example, thick plate glass, see Figure 7, which furnishes a very smooth and satisfactory surface over which to spread a thin film of ink in such a manner that the fingers may be impressed thereon and enough ink 15 removed thereby to enable them to transfer their lines and markings to the blank or record sheet on which they will be immediately thereafter re-impressed in the manner I shall presently point out. It is desirable 20 that this ink-applying surface should be readily removable for cleansing, and that it should also be locked very securely and immovably when in use, and to this end therefore I provide one end thereof with a 25 notch 21 having a beveled bottom face which takes under and firmly engages a beveled lip 19 formed on the casting 4 at the upper end of one of the arms 3, see Figures 3 and 7, while the opposite end of plate 6 is similarly notched or recessed at 26 to provide an 30 inclined surface that is engaged by a lock or catch 22 pivoted by means of a pivot 24 on the other casting 4 at the upper end of the other arm 3, said catch having a handle 35 consisting of a small rigid pin 23 for easily operating it, and being provided with a spring 25 which is so tensioned that it holds the clamp 22 firmly down in the recess 26 when the plate 6 is locked in place for use. 40 By removing the catch 22 from recess 26 the platen 6 will be quickly released and can be withdrawn endwise from its position under the stationary lip 19.

The main finger-printing table or impression bed is a substantially horizontal plate or surface 11 supported between the uprights 2, 2, near the upper ends thereof, the same being rather narrow in its width, but of sufficient strength to easily stand the impression of the fingers thereon in registering the prints and impressions. The precise mode of supporting the main table 11 may vary widely, but in the present example of mechanism I support it on the forwardly-projecting arms 7, 7, of the uprights 2, 2. This table is screwed near each end by one or more screws 51 to a stud, lug, or cleat or cleats 52, projecting from or cast integral with the arms 7, see Figures 6 and 9, to assist in supporting the table on the arms 7, 7. Further the front edge of table 11 is provided with a parallel roller 10, which may be revoluble or stationary, and is journaled in bearings 53 that are secured to the table by means of screws 54.

The record blank, filing card, or other sheet of paper, cardboard, or any other suitable material, and of any size, shape and design, on which the prints of the thumb and fingers are registered by the subject, an example of which sheet is given at 36, is placed upon the table 11, and is propelled across the face of the same by feed rollers, all that part of the sheet except that which is directly exposed for printing being folded back 75 underneath the table or fed back through the machine out of the way. In order to properly position each sheet in this way, and to clamp it at times, and feed it at other times, I have devised selected devices 80 for these purposes. Thus I employ a front clamping plate 8 having an upper curved edge 8^a which fits over the roller 10 and is arranged and adapted to hold the sheet 36 between the roller 10 and the curved member 8^a, the plate 8 being then in an inclined position below roller 10 and holding the sheet 36 back under the table where it will not be crumpled or smudged while the printing operation is being performed, but will be kept fresh and clean for other records to be made thereon as it is fed forward. This plate 8 is provided at each end with an arm or link 9 that is movably supported by a pivot 17 on the projecting frame member 7 95 nearest thereto, so that said plate 8 and its curved edge 8^a may be lifted away at times from the front edge of the table 11 and the roller 10, or lifted from the position shown in full lines in Figure 8 to the position shown 100 in dotted lines in the same figure, such manipulation of plate 8 being performed by laying hold of the lower edge of the plate. To the links 9 are fastened springs 13 that pass down through slots 12 in table 11 and 105 are secured to the frame members 7 or other stationary parts, and which have the effect of holding the plate and its curved edge 110 with a tight clamping effect on the record sheet after being lowered into clamping position.

The feed rollers for moving the record sheet 36 across the face of table 11, so that after one row of prints has been obtained a fresh space may be provided for the next 115 row and so on, are usually two in number, a smaller upper roller, as 32, and a larger lower roller or drum, as 14. One of these, as 14, has a handle 16 on one end thereof for rotating it, and roller 14 has a shaft 15 120 which is journaled in the uprights 2, 2. The roller 32 may have the same diameter throughout, or be provided at intervals with two or more pressure rings 35, and this upper roller is likewise journaled in uprights 125 2, 2, and in slots 33, there being adjusting screws 34 in the upper ends of the members 2, 2, that bear on roller 32 and regulate its tension on the sheet. These rollers are situated directly adjacent to the rear edge of 130

the table 11, and the record sheets will have their rear edges introduced from the surface of the table into the space between the rollers, and as soon as the rollers grip the card 5 or paper it may be fed along by the rotation of the rollers effected by turning the handle 16.

The ink supplying devices are conveniently arranged on the base 1, within the frame, 10 and below the impression table, so that they will be within easy reach but not obtrusive or in a place to interfere with the work of the machine, see Figure 3. They consist of an ink roller 42, which when not in use is 15 supported on V-notched lugs 43 rigid on base 1, the roller 42 having projecting journal pins 55 that enter the V-notched lugs 43 so as to keep the roller 42 out of contact with the base and thus prevent the deposit of ink 20 on the latter, while the handle of the roller has a pin 56 to prop it up at the same time. 44 denotes a cup to hold an ink supply or receive a well containing such supply. 37 denotes a circular table on which the roller 25 distributes the ink preparatory to transferring thin films or coatings thereof to the ink-applying platen 6, said table 37 having a central vertical journal 38 carried loosely in a socket in the end of a horizontal arm 39, 30 the other end of which arm has a vertical journal pin 40 that lies loosely in a bearing 57 on the side of a frame piece 2. The journal pin 40 has a disc or shoulder 48 thereon, between which and a part of bearing 35 57 a spring 41 is tensioned, the same having the effect of holding the pin 40 in its bearing except when it is raised to swing the arm 39 in or out. When table 37 is not in use it will be moved in and lie between the uprights 40 2, 2, and over base 1, as shown in Figure 3; but when in use the arm 39 will be swung out as shown in Figure 4, by turning it on its pivot pin 40. When the table 37 is idle 45 a catch pin 45 on the underside of arm 39 enters a recess 46 in bearing 57, see Figure 5, and spring 41 keeps them engaged; but when the table is to be used the arm 39 will be lifted, overcoming spring 41 and disengaging pin 45 from recess 46, after which the arm will be turned out and the pin 45 will drop into hole 47 and lock the arm and table in their outer active position. The lifting of arm 39 is accomplished by simply turning it on its pivot which causes pin 45 50 to ride up the inclined bottom of recess 46.

The method of using this device for forming and preserving finger prints of subjects will be evident to those familiar with finger printing, without supplementing the previous mechanical description at any length. When the machine is set for use the parts will be as represented in Figure 1, where the extension arms 3 are vertically above the uprights 2, thus supporting the ink-applying platen 6 in a convenient inclined position

for inking the fingers. The extension arms 3 are securely held in this position by the winged clamping screws 27 that are engaged by the slots 28 in the arms 3 near the end thereof and which screw into the uprights 2. 70 Also the record sheet 36 will lie on the table 11, as shown in Figure 8 and in dotted lines in Figure 6, being kept immovable by the front clamping device 8. After the ink has been evenly distributed on the table 37 the 75 roller 42 can transfer and spread the same on the platen 6 so that the fingers may be applied thereto and coated with enough ink to make the proper registry on sheet 36. As soon as the fingers are inked they will be applied one by one or several simultaneously or otherwise to the surface of sheet 36 and the prints made thereon. As soon as one set of prints is complete, the record sheet 80 can be released and fed forward by turning handle 16 so that a space on the sheet will be in readiness for the next set of prints. When the operation is over and it is desired to close the machine, the arms 3 will be folded down as shown in Figure 2, after first 85 loosening the thumb nuts 27, and in order to make the closing of these members as compact as possible, the arms 3 have slots 29 which in this position engage the thumb nuts 27 which can then be tightened to hold the arms 3 in the closed position, and said arms 3 have also recesses 30 that partly embrace the shaft 15 of the feed drum 14. When the parts are thus compactly interclosed the machine occupies a small space 90 and can be easily housed, boxed or carried about. The simplicity of the construction, and the small number of parts, contribute to the ease of operation, and make it possible for rapid and extensive use and the printing 95 of the fingers of a very large number of persons in a short time; besides giving to this art a successful portable machine, which is so light and well proportioned that it may be carried about with very little trouble. 100

Many changes and varieties within the terms and scope of the appended claims may be made without departing from the invention, and I reserve a wide liberty and privilege in this respect. 115

Having thus described my invention, what I claim as new and desire to secure by Letters Patent is:

1. In an apparatus for taking and preserving finger-print impressions, the combination with the frame having uprights and foldable extension arms pivoted to said uprights, of an impression bed supported between the uprights, and an ink-applying platen carried by the foldable arms. 120

2. In an apparatus for taking and preserving finger-print impressions, the combination with the frame having uprights and foldable extension arms pivoted to said uprights, of means for clamping the arms 125

in open position and likewise in folded position, an impression bed supported between the uprights, means for feeding the record sheet over the impression bed, means for holding the sheet firmly on said bed, and an ink-applying platen carried by the extension arms.

3. In an apparatus for taking and preserving finger-print impressions, the combination with the frame having uprights and foldable extension arms pivoted to said uprights, of means for clamping the arms in open or in folded position, consisting of thumb screws carried in the uprights and adapted to engage one or the other of the members of a pair of slots in each arm to clamp the arms in their different positions, an impression bed supported between the uprights, and means for holding and for feeding the record sheet in relation to the bed.

4. In an apparatus for taking and preserving finger-print impressions, the combination with the frame having uprights and foldable extension arms, the latter being slotted, and the uprights having clamps to engage the slotted portions of the arms, an ink-applying platen carried by the arms, an impression bed supported between the uprights, a front roller supported on the edge of said bed, a paper clamp arranged in front of said roller, and a feed device for the recording sheets arranged at the rear of the said bed.

35 5. In an apparatus for taking and preserving finger-print impressions, the combination with the frame having uprights and foldable extension arms, the latter being slotted, and the uprights having clamps to engage the slotted portions of the arms, an ink-applying platen carried by the arms, an impression bed supported between the uprights, a front roller supported on the edge of said bed, a paper clamp arranged in front of said roller, and a feed device for the recording sheets arranged at the rear of the said bed, said feed device consisting of an upper roller and a lower roller which receive the recording sheets between them, 50 one of said rollers having a handle for rotating it.

6. In an apparatus for taking and preserving finger-print impressions, the combination with the frame having uprights and foldable extension arms pivoted to said uprights, of an ink-applying platen carried by the foldable arms, an impression bed supported between the uprights, a roller journaled in bearings at the front edge of the bed, a pivoted clamping plate in front of the said roller, and a pair of rear feed rollers, one of which bears adjustably on the record sheet, and the other of which is provided with a handle for rotating it.

65 7. In an apparatus for taking and pre-

serving finger-print impressions, the combination with the frame having uprights and foldable extension arms pivoted to said uprights, of an ink-applying platen carried by the arms, an impression bed supported between the uprights, a roller carried by the bed, a clamping plate in front of the roller having a lip and provided with end links pivoted to the uprights, said links having springs connected to the frame for holding the clamping plate against the roller, and a pair of feed rollers at the rear of the bed, one of which is provided with means for regulating its tension, while the other is relatively larger and has an operating handle.

8. In an apparatus for taking and preserving finger-print impressions, the combination with the frame having uprights and foldable extension arms pivoted to said uprights, of an impression bed supported between the uprights, and an ink-applying platen carried by the foldable arms, said platen being removably arranged, and at one end loosely engaging a projection on the frame, together with a pivoted spring-provided catch at the other end of the platen for clamping it firmly in position but adapted to release it for cleaning.

9. In an apparatus for taking and preserving finger-print impressions, the combination with a frame having a base and uprights, of a finger-inking platen supported thereby, an impression bed or table mounted between the uprights, a front roller having journals carried by said table, a clamping plate having a curved lip that partially surrounds the roller and also a rearwardly-inclined lower portion, said plate being provided at its ends with links pivoted to arms on the uprights, and a pair of feed rollers at the rear of the impression bed, one of which is formed as a drum and is provided with a handle for revolving it.

10. In an apparatus for taking and preserving finger-print impressions, the combination with a frame having a base and uprights, of a finger-inking platen supported thereby, an impression bed or table mounted between the uprights, a front roller having journals carried by said table, a clamping plate having a curved lip that partially surrounds the roller and also a rearwardly-inclined lower portion, said plate being provided at its ends with links pivoted to arms on the uprights, and a pair of feed rollers at the rear of the impression bed, one of which is formed as a drum and is provided with a handle for revolving it and the other of which has pressure members, together with adjusting screws arranged in the uprights and bearing on said roller, so that the tension of the pressure members on the recording sheet may be varied as desired.

11. In an apparatus for taking and pre-

serving finger-print impressions, the combination with a frame having a base and uprights, of a finger-inking platen supported thereby, an impression bed or table mounted between the uprights, a round member having journals, bearings for said journals secured to the bed, a clamping plate having a curved lip that partially surrounds the round member and also a rearwardly-in-

clined lower portion, said plate being provided at its ends with links pivoted to arms on the uprights, and a pair of feed rollers at the rear of the impression bed, one of which is formed as a drum and is provided with a handle for revolving it.

In testimony whereof I hereunto affix my signature.

PATRICK RYAN.
